UNITED STATES PATENT OFFICE.

FRANCIS H. NILES, OF CHICAGO, ILLINOIS, ASSIGNOR TO FEATHERSTONE FOUNDRY AND MACHINE COMPANY, OF CHICAGO, ILLINOIS, A CORPORATION.

FLUID-PRESSURE MOTOR.

No. 801,332.

Specification of Letters Patent.
Application filed May 23, 1904. Serial No. 209,226.

Patented Oct. 10, 1905.

To all whom it may concern:

Be it known that I, FRANCIS H. NILES, a citizen of the United States, and a resident of Chicago, county of Cook, and State of Illinois, have invented certain new and useful 5 Improvements in Fluid-Pressure Motors for Reciprocating Hammers and the Like, of which the following is declared to be a full, clear, and exact description.

10 The improvement relates to reciprocating steam or pneumatic motors for actuating forging-hammers or like tools in which the tool is carried directly upon the reciprocating element of the motor.

15 The invention seeks to provide simple and effective valve mechanism by which the operation of the motor may be readily controlled and which will automatically prevent the bounding of the motor piston upon its

to cushion the return or idle stroke of the piston and prevent its pounding against the rear 55 cylinder-head.

The valve mechanism preferably comprises a main valve 18 between the pipes or passages 16 and 17 and a supplemental valve 19 in the pipe or passage 17 to the rear end of 60 the cylinder. The main valve 18 is preferably of rotary type contained within a cylindrical casing 20. Passages 21 and 22, preferably formed in cored bosses on opposite sides of the valve-casing, communicate with 65 the passages or pipes 16 and 17. An exhaust-port 23, formed in the side of the valve-casing between the passages 21 and 22, communicates with an exhaust-chamber 24, the walls of which are preferably cast in piece 70 with the body of the valve-casing. An exhaust-pipe 25 leads from the chamber 24, and

- ver and said supplemental valve, whereby the latter is open when said main valve is shifted to effect the working stroke of said piston.
- 5 11. In fluid-pressure motors for reciprocating hammers and the like, the combination with the cylinder, piston and piston-rod, of a main-valve casing, a passage between said casing and the opposite ends of 10 said cylinder, inlet and exhaust ports in said casing, a rotary valve therein for alternately connecting said passages with said inlet and exhaust ports, an operating-handle for said valve, a supplementary rotary valve in the 15 passage leading to the rear end of said cylinder, an arm on the stem of said supplemental valve, a spring-held tappet-bar actuated by said piston at the end of its return or idle stroke, a pivoted pawl on said tappet-bar arranged to engage said arm and close said supplemental valve and a link pivoted to said hand-lever and having a pin-and-slot connection with said arm for opening said supplemental valve.
- 20 12. In fluid-pressure motors for reciprocating hammers and the like, the combination with the cylinder, piston and piston-rod, of inlet and exhaust passages opening into opposite ends of said cylinder, a valve 25 controlling the passage leading to the rear end of said cylinder, shift mechanism for 30 closing said valve arranged to be actuated by said piston-rod at the end of the return or idle stroke of said piston and means for opening said valve. 35
13. In fluid-pressure motors for reciprocating hammers and the like, the combination with the cylinder, piston and piston-rod, of inlet and exhaust passages opening 40 into opposite ends of said cylinder, a valve 45 controlling the passage leading to the rear end of said cylinder, adjustable tappet mechanism for closing said valve actuated by said piston on its return or idle stroke, and means for opening said valve. 50
14. In fluid-pressure motors for reciprocating hammers and the like, the combination with the cylinder, piston and piston-rod, of inlet and exhaust passages opening 55 into opposite ends of said cylinder, a rotary valve controlling the passage to the rear end of said cylinder, an arm on the stem of said valve, a shiftable bar, a pivoted spring-held tappet-lever arranged to be shifted by said piston-rod on the return or idle stroke of said piston, a pivoted pawl on said bar arranged to engage said valve-arm and close said valve and means for opening said valve. 55
